UNITED STATES PATENT OFFICE

2,441,118

APPARATUS FOR THE MANUFACTURE OF
SEAMLESS VARICOSE-VEIN STOCKINGS

Louis Boucraut, Troyes, France, assignor to Société à Responsabilité Limitée: Les Fils De Valton & Co., Troyes, France

Application October 25, 1945, Serial No. 624,462
In France December 30, 1941Section 1, Public Law 690, August 8, 1946
Patent expires December 30, 1961

4 Claims. (Cl. 66—132)

1

Heretofore seamless varicose-vein stockings have been manufactured by means of a hand knitting machine. In the course of this operation, the heel and the sole of the stocking were knitted back on the needles, involving lengthy and costly manufacture and moreover allowing only of a small output. Moreover, on such machines, the use of the elastic required the work of a skilled operator, as most applications were made by hand, which often led to irregularities in the distribution of elastic and in defects in the finished stocking.

The present invention, which has for its object to eliminate a large part of the above drawbacks, consists in providing means for manufacturing seamless varicose stockings, with inlaid or knitted elastic yarn, by the use of automatic knitting machines such as are already in use in the hosiery art for the manufacture of stockings and socks and known by the name of Scott or Maxim machines.

It is known that in such machines the changes of yarn are effected automatically by means of a counter in a similar way as for the manufacture of the leg of the stocking, of the heel or of the sole.

It is also known that, in such machines, the manufacturers or the users had already achieved the possibility of introducing the elastic so as to provide at the top of an ordinary sock or half-hose an elastic band intended to serve as a garter.

It had not yet been suggested to insert the elastic yarn on such machines throughout the whole length of the leg and the foot so as to obtain (seamless) varicose stockings.

This insertion of the elastic yarn throughout the entire surface of the article by means of automatic machines of the above defined type gives rise to certain technical problems whereof the solution also constitute in itself an object of the invention.

Such problems all originate in the progressive tension which should be imparted to the elastic yarn so that the article should finally have the desired shape.

The invention thus has also for its object to combine an automatic hose knitting machine with a system for the feeding and the progressive tensioning of the elastic yarn, said system being of any suitable type and in particular having the character defined hereafter.

The appended drawing represents schematically several devices capable of achieving this purpose, and whereof the application to a circular

2

automatic hose knitting machine constitute the chief feature of the invention.

In such drawing, Fig. 1 is a schematic plan view of an apparatus constructed in accordance with my invention showing the adjustable tension feeding device for the yarn; Fig. 2 is a schematic plan view of the device for disengaging and for maintaining the tension of the elastic yarn; Fig. 3 illustrates the device for attaining and maintaining the normal feeding of the elastic yarn under normal conditions of tension; and Fig. 4 is a profile view of the grooved disc and adjacent parts of Fig. 3.

1. Progressive tension device

15 In the ordinary automatic knitting machine for socks and stockings, the elastic yarn is fed to the machine under a uniform tension, controlled by hand but which may not be altered 20 during the manufacture of the stocking. In the system according to the invention, a feeding device with adjustable tension has been interposed as shown in Fig. 1.

25 On the path of the elastic yarn is installed a rough disk or plate 1, against which bears a loose roller 2 under slight pressure and the axis of which is parallel to a radius of the plate 1. This plate 1 is rotated by a shaft 3, whereon is mounted a conical drum 4 driven by means of 30 a second conical drum 6 through a belt 5, said second drum 6 being opposingly mounted with respect to the first and being driven in uniform rotation by the machine.

The belt 5 connecting both drums passes 35 through a yoke 7 displaceable along the cones 4 and 5 and thus imparting to the first cone 4 a variable speed, thus driving the disk 1 at a variable speed. The elastic which passes between the loose roller 2 and the disk 1 is thus fed to the 40 machine at a variable rate, thus providing a variable tension to the elastic as it engages the needles of the machine. There results in the finished articles a more or less large width of the stocking.

45 By a suitable displacement of the yoke 7, there may thus be given a large transverse dimension to the stocking at the location of the calf, a smaller dimension at the ankle, etc. To obtain such progressive displacement of the yoke 7, 50 said yoke is connected by a square bent lever 8 oscillating about an axis 9 and by a link 10 to a roller 11 engaging the periphery of a cam 12 driven by the general motion of the machine and against which said roller is at all time urged by a spring 13. The outline of the cam 12 is such

as to impart to the roller 11 and consequently to the yoke 7, the displacement required to obtain the desired tension of the elastic.

The elastic yarn is fed to the disk 1 by an eye 14 connected in turn to the nut of a worm 15 parallel to the axis of the roller 2. By rotating the worm 15 by hand, the eye 14 is raised or lowered along a radius of the disk 1, whereby the average tension of the elastic may be adjusted, disregarding the action of the cam 12, and a more or less tight fitting stocking may be obtained.

2. Device for disengaging and for maintaining the tension of the elastic yarn

At the start of the heel and at the termination of the sole, the elastic yarn must be disengaged from the needles and maintained under tension at rest. Such holding under tension is necessary to avoid a defect in the stocking at the moment where the elastic is again engaged by the needles.

A particular device described hereinafter by way of example, and illustrated at Fig. 2, makes such a result possible:

The loose roller 2 is fixed to a lever 16-18, pivoting about a fixed fulcrum 17 and the second arm 18 thereof is urged backwardly by a spring 19 so as to resiliently urge the loose roller 2 against the disk 1. Said second arm 18 bears on the other hand against one arm 20 of a bent lever pivoting about a fixed fulcrum 22, whereof the second arm 21 is connected through a link 23 to the usual yarn feeding arm 24. When said yarn feeding arm 24 rises to cast off the elastic yarn C from the needles A, the link 23 pushes the bent lever 21 which in turn pushes the two armed lever 16-18 and withdraws the roller 2 from the disk 1. At that moment, the elastic ceases to be drawn by the disk 1. On the other hand, a member 25 of the lever 20 acts to clamp the elastic against a fixed member 26, and thereby holds the elastic while maintaining the same under tension.

3. Regular feeding device of the elastic

In order to render the machine automatic, it is necessary to achieve a continuous and uniform feed of the elastic, which may not be achieved by even the best winding device. It is therefore necessary to insert on the path of the elastic a device, eliminating the irregularities of tension occurring at the exit of the elastic creel. The device represented by way of example in Figs. 3 and 4 provides a means for achieving a regular tension of the elastic under very satisfactory conditions.

A disk 27 having a V-shaped groove 28 is fixed to a drive pulley P, holding a belt C, and rotating at high speed; the cross section of the groove 28 is determined in such manner that when the elastic yarn is placed at the bottom of said groove, and about approximately $\frac{3}{4}$ of the periphery of the disk, it is driven without any sliding motion thereof, being so to speak ripped off the creel B.

The elastic yarn passes through a fixed eyelet 29, then into the groove of the disk 27, into the eyelet 30 of a balance member 31, then into a fixed eyelet 32, wherefrom it departs to feed the machine.

The member 31 pivots about an axis 33 and comprises a very light counterweight 34 surging the member 31 back in the direction of the arrow f. When the pîrn exerts no tension, the elastic arrives freely and the member 31 is in the backward position (shown in dots and dashes); the

elastic then slides into the groove 28 of the disk 27.

As soon as the pîrn exerts a pull, the member 31 is immediately drawn forward by the slight tension which occurs; the elastic adheres to the bottom of the groove 28 of the disk 27 and is strongly drawn by disk 27; the pull ceases immediately, the tension disappears and the member 31 returns to its forward position.

This invention is applicable both in the event where the elastic is inlaid in the stocking and where it is knitted into it. In the latter case, the heel may be made of elastic or nonelastic yarn at will; similarly, the reverse may be made of elastic or nonelastic yarn. A simple alteration of the usual cams of the counter enables passing from one type of stocking to the other.

The process described above, and the stocking obtained by means of this invention, comprise several advantages.

By reason of its manufacture on a circular automatic knitting machine, the stocking comprises no longitudinal seam and thereby does not comprise any additional thickness which could injure the leg of the wearer. In manufacture, there is no risk of cutting the elastic yarn by the sewing machine as in the stocking with a longitudinal seam.

The machine employed allows for changing at different points of the stocking the yarn being fed, and therefore for reenforcing the heel at will, for inserting or suppressing the elastic at desired points, etc.

Moreover, the machine being entirely automatic, does not require particularly skilled labor, while providing a high output, therefore a low cost of production, and on the other hand comprises only a single needle cylinder whereby a very fine stocking may be obtained.

What I claim as my invention and desire to secure by Letters Patent is:

1. In an automatic circular hose knitting machine for knitting seamless varicose-vein stockings, a device for putting the elastic yarn under progressive tension, comprising a rotary disk, a roller for pressing the elastic yarn against said rotary disk, two conical pulleys having their axes parallel and opposingly disposed with respect to each other, a belt transmission means to transfer rotation from one of said pulleys to the other, a lever system for actuating said belt and a cam means for actuating said lever system.

2. In an automatic circular hose knitting machine for knitting seamless varicose-vein stockings, a device for putting the elastic yarn under progressive tension, comprising a rotating disk, a roller for pressing the elastic yarn against said rotary disk, and a lever system operatively connecting the yarn feeding arm of the machine with the said roller-cooperating with said rotating disk, to cause said roller to become operative.

3. In an automatic circular hose knitting machine for knitting seamless varicose-vein stockings, a device for putting the elastic yarn under progressive tension, comprising a rotating disk, a roller for pressing the elastic yarn against said rotary disk, and a lever system operatively connecting the yarn feeding arm of the machine with the said roller-cooperating with said rotating disk, to cause said roller to become operative, and means for blocking said elastic yarn under tension when the roller is inoperative, said means being actuated by said lever system.

4. In an automatic circular hose knitting machine for knitting seamless varicose-vein stockings, a device for putting the elastic yarn under

progressive tension, comprising a rotating disk, a roller for pressing the elastic yarn against said rotary disk, a means for momentarily blocking said elastic yarn under tension and a means for providing continuous and regular feed of the elastic yarn comprising a grooved disk for passing said elastic yarn and a tiltable means becoming operative under the action of an abnormal pull on the elastic yarn for determining said elastic yarn to be drawn by said grooved pulley.

LOUIS BOUCRAUT.
